Application June 13, 1931, Serial No. 544,168. Re-
newed February 7, 1935. In Switzerland June
14, 1930

10 Claims. (Cl. 91—39)

This invention relates to a device for cleaning, waxing and polishing floors, linoleum and the like.

Floor polishing apparatuses are known, in which in a casing, serving for accommodating the wax, a pressure plate is arranged, which is gradually moved downwards, either directly by hand or automatically by the oscillating movements of the handle during the waxing, in order in this manner to feed the wax into the lower portion of the device serving for waxing.

All these apparatuses are however open to a great objection in that whilst they are suitable for applying the wax to the floor or the like to be treated, the wax is not distributed film-like on the floor. A further disadvantage of the known devices consists, in that the polishing apparatuses serve either only for applying the wax or for polishing the floor smeared with wax.

All these disadvantages are overcome by the invention in that an apparatus is produced, by means of which the floor can be smeared with wax, which is at the same time distributed film-like over the floor.

The apparatus according to the invention serves, besides for applying and distributing the wax, also for polishing the floor in that, either the distributing brush is replaced by a polishing brush the wax feed being automatically shut off, or the entire apparatus is fixed on a separate polishing brush, when the wax feed is also shut off.

A technical advance of commercial importance is attained by the invention.

According to the invention in a waxing apparatus, in which a pressure plate is fitted in a wax container in such a manner that it automatically gradually descends during work and consequently presses the necessary quantity of wax through brushes provided with holes and forming the bottom of the wax container, a cloth for applying the wax is stretched and clamped over the applying brush by means of an exchangeable frame, provided with distributing or polishing bristles.

Instead of the frame fitted with bristles, serving for clamping the cloth, a frame of rectangular cross section may be employed, in which the vertical inner side surfaces serve as clamping surfaces for the cloth for applying the wax and the horizontal surfaces for fixing the distributing or polishing brush.

During the up and down movements of the handle during the waxing a pawl, connected to the handle by a lever, rotates through a certain distance a vertically arranged ratchet wheel.

This wheel transmits the rotation by means of a toothed wheel gearing to a screw spindle which actuates the plate in the wax container so that the wax is automatically pressed through apertures provided in the brush back into the application brush.

The shutting off of the wax feed is effected in that an oscillatable lever engages in a groove provided on the pawl and thus pushes the pawl of the ratchet wheel.

During the return movement of the control lever the pawl is again pressed against the teeth of the ratchet wheel by means of spring pressure.

The pawl is connected to the handle by a lever so that during the return movement of the handle the wax feed is actuated.

The oscillatable lever for pressing off the pawl is mounted so that it can be brought, as desired, into and out of engagement with the ratchet wheel.

In order to employ the device as polishing apparatus, it is preferable to construct the polishing brush as a solid block. In this instance a hollow space is provided in the brush back, which serves for accommodating the apparatus with applying brush and cloth covering. A bar attached to the brush back of the solid block serves as an interrupter for the wax admission.

This bar has a cam-shaped edge, in which a pin fitted on the disengaging mechanism engages when inserting the device into the block. It must follow the curve of the bar and is thereby moved so that the feed pawl is disengaged from the toothed wheel.

In the frame, which stretches the cloth over the application brush, a slot is provided through which the disengaging bar extends.

The block brush can evidently also be constructed as an ordinary block brush with angle bars fixed thereto so that the entire apparatus, including the distributing brush, can be fixed thereto. The fixing can be effected as desired, by means of a latch on each bar or in any other manner.

As in this construction of the block brush the distributing brush remains in the apparatus, it is provided with a slot for introducing the disengagement bar. This is preferably widened in downward direction so that the bar can easily slip through the slot.

An embodiment of the invention is illustrated by way of example in the accompanying drawing in which:

Fig. 1 is a cross section of the apparatus for applying and distributing the wax.

Fig. 2 is a similar view showing the apparatus fitted for polishing the floor.

Fig. 3 is a perspective view of a stretching frame.

5 Fig. 4 is a perspective view of a polishing brush constructed as a solid block.

Fig. 5 is a side elevation of the entire apparatus fitted for applying and distributing the wax, the protecting cover being removed.

10 Fig. 6 is a similar view to Fig. 5 showing the apparatus with the block brush.

Fig. 7 shows in perspective view a modified form of construction of the block brush.

15 Fig. 8 shows in perspective view the block brush according to Fig. 7 with the distributing apparatus mounted thereon.

A container 1 for accommodating the wax is closed at the bottom by an applying brush 2. Over this brush 2 a cloth 3 is stretched. This 20 cloth 3 is clamped in position by the wooden frame of a distributor brush 4 or of a polishing brush 5. The brushes have a felt layer 6 around the brush back for the purpose of protecting furniture, walls and the like.

25 Fig. 9 shows in perspective view the apparatus if the apparatus is to be employed for applying wax, it is provided with a distributing brush 4 (Fig. 1), whereas for polishing it is provided with a block brush 5. The bristles of the brushes extend slightly lower than the surface of the 30 cloth, so that this latter does not come into contact with the floor.

For clamping the cloth 3 a frame 8 might be employed. This frame 8 is preferably of rectangular cross section, the vertical inner faces serving as clamping surfaces for the cloth 3 and the horizontal faces for the fixation of a distributor brush or polishing brush.

The frame 8 is not essential but the cloth may be held in place by friction alone between the 40 brush 4 and container 1.

The movement of the pressure plate 7, which presses the wax out of the container 1 through the apertures in the brush 2, is effected during the up and down movement of the handle 9 by 45 means of a feed pawl 10 which rotates through a certain distance a vertically arranged ratchet wheel 12 through the intermediary of a lever 11. This ratchet wheel 12 imparts its rotary movement to the pressure plate 7 by means of any 50 suitable known toothed wheel gearing, which rotates a spindle 13.

A lever 14 is provided for disengaging the pawl 10 and consequently shutting off the wax supply, said lever engaging during the oscillation of the 55 handle in a depression or groove provided in the pawl 10 and thus presses the pawl 10 away from the ratchet wheel 12, whereas during the return oscillation of the lever 14 this pawl is pressed against the teeth of the ratchet wheel 12 by spring 60 pressure. The handle fixing is constructed as a U-shaped bow 15 and connected with the pawl 10 actuated by the lever 11, 16.

The lever 14 is arranged oscillatable in such a manner that by means thereof the pawl 10 can 65 be brought into and out of engagement as desired.

The polishing brush can also be constructed as a solid block 17, a special device 19, 20 being provided on the brush back 17 for interrupting 70 the wax feed.

The interrupting device consists preferably of a bar 19 with upper edge 20 of cam-shape, so that a pin 21 on the lever 14 is moved during the insertion of the device into the block aperture 18 75 in such a manner, that the pawl 10 is disengaged

from the toothed wheel 12. In the frame 8 a slot 22 is provided through which the bar 19 is inserted during the placing of the applying brush 2 with cloth covering 3 on to the block brush 17.

The block brush may be constructed as a simple brush 23 with angular bars 24 fixed thereto, so that the entire device including the distributing brush 4 can be fitted on the block brush 23. In this instance a pin 25 serving as stop is fitted on the bar 19. For fixing the apparatus on the block brush 23 latches 26 may be provided, which can be pushed into apertures 27 provided in the bars 24.

It is evident that it lies within the scope of the invention to effect the fixing by means of any known devices.

After the floor or the like has been rubbed over with wax and this wax has been distributed film-like by means of the distributing brush 4, the entire apparatus, including the distributing brush 4, 20 is placed and fixed on the block 23. The wax feed is hereby automatically shut off, as the cam 20 pulls the pawl 10 out of engagement with the toothed wheel 12 through the intermediary of the lever 14.

I claim:

1. An apparatus for waxing and polishing floors, comprising in combination a wax container, a perforated wax applying brush forming the bottom of said container, a frame of rectangular cross section adapted to be slipped over said applying brush and having a horizontal surface and a downwardly extending flange, a frame shaped distributing brush exchangeably mounted on the horizontal surface of said frame, and a wax applying cloth adapted to be stretched over said wax applying brush and clamped between said flange and said container.

2. An apparatus as specified in claim 1, comprising in combination with the wax container and the plate, a handle attached to said container, a screw spindle adapted to lower said plate in said casing, a ratchet wheel on said container, a toothed wheel gearing connecting said ratchet to said screw spindle, and a pawl connected to said handle adapted to rotate said ratchet wheel and to transmit the up and down movement of said handle to said screw spindle.

3. An apparatus as specified in claim 1, comprising in combination with the plate, a screw spindle adapted to lower said plate, a ratchet adapted to operate said screw spindle, a pawl having a groove and adapted to actuate said ratchet, a lever adapted to engage in said groove of said pawl to disengage said pawl from said ratchet wheel, and a spring adapted to press said pawl against said ratchet wheel on the disengaging of said lever.

4. An apparatus as specified in claim 1, comprising in combination with the container and the plate, a U-shaped bow on said container, a handle fixed in said bow, means for lowering said plate, a pawl adapted to actuate said means, and levers connecting said pawl to said bow.

5. An apparatus as specified in claim 1, comprising in combination with the container and the plate, means for lowering said plate, a ratchet wheel connected with said means, a pawl for operating said ratchet wheel, and an oscillatable lever adapted to bring and lock said pawl in and out of engagement with said ratchet wheel as desired.

6. An apparatus as specified in claim 1, comprising in combination with the applying brush and the cloth stretched thereon, a solid block

brush having a cavity for accommodating said applying brush and said cloth, and a device on the back of said solid block for interrupting the wax feed.

5 7. An apparatus as specified in claim 1, comprising in combination with the applying brush and the plate, a solid polishing block adapted to be fitted on said applying brush, a bar on the back of said block, a cam-shaped edge on said bar, a 10 disengaging device adapted to engage said cam-shaped edge, a ratchet adapted to effect the lowering of said plate, and a feed pawl engaging said ratchet adapted to be disengaged from said ratchet by said pin during the insertion of the 15 device in said block brush.

8. An apparatus as specified in claim 1, comprising in combination with the frame having a slot the applying brush and the cloth covering,

a block brush adapted to carry said applying brush and said cloth, and bars adapted to engage in said slot during the placing of said applying brush with said cloth on to said block brush.

9. An apparatus as specified in claim 1, comprising in combination with the distributor brush, a block brush constructed as an ordinary brush, and angular bars on said block brush adapted to receive the entire apparatus including said distributor brush. 5 10

10. An apparatus as specified in claim 1, comprising in combination with the distributor brush, a block brush adapted to be placed on said distributor brush, bars on said block brush, and a pin on said bar adapted to serve as stop for said distributor brush. 15

MAX PLÖN.
